W. C. ROBBINS.
RUFFLING MECHANISM FOR SEWING MACHINES.
APPLICATION FILED JAN. 22, 1916.

1,242,476.

Patented Oct. 9, 1917.

UNITED STATES PATENT OFFICE.

WILLIS C. ROBBINS, OF WAKEFIELD, MASSACHUSETTS, ASSIGNOR TO LUCIUS N. LITTAUER, OF GLOVERSVILLE, NEW YORK.

RUFFLING MECHANISM FOR SEWING-MACHINES.

1,242,476.

Specification of Letters Patent.

Patented Oct. 9, 1917.

Application filed January 22, 1916. Serial No. 73,505.

To all whom it may concern:

Be it known that I, WILLIS C. ROBBINS, a citizen of the United States, residing at Wakefield, in the county of Middlesex and 5 State of Massachusetts, have invented certain new and useful Improvements in Ruffling Mechanism for Sewing-Machines, of which the following is a specification.

This invention relates to sewing machines, and more particularly to improved attachments therefor which can be readily thrown into and out of operation, it especially relating to improved ruffling and cloth folding attachments which can be 10 readily thrown out of position to enable the operator to end up the stitching of a circular piece when the beginning of the stitched or ruffled portion feeds around to a position in front of the needle, so that the 15 ruffling blade may be removed from operative position and the cloth folder withdrawn from the goods and shifted to a position out of the way so that no obstructions remain in front of the needles to hinder or 20 interfere with the finishing or starting of the work. The improvements are also useful where a machine is used part of the time as a ruffling machine and part of the time as a plain stitcher for lap seam fell- 25 ing, etc.

In the drawings accompanying and forming part of this specification, Figure 1 shows sufficient of the front end of a top shaft Metropolitan ruffling machine to illustrate, these improvements applied thereto, the full lines showing the ruffling blade in working position and the dotted lines its inoperative position, while certain parts of the cloth folding attachment are shown in 30 section; Fig. 2 is a front view of Fig. 1 looking in the direction of the arrow, Fig. 1, and shows the cloth folder in dotted lines in its non-working position; and Fig. 3 is a perspective detail view of the part 35 for supporting the cloth folder.

Similar characters of reference indicate corresponding parts in the different figures of the drawings.

It will be understood that the present improvements may be applied to and used 40 with any top ruffling sewing machine and that the machine has the usual feeding and stitching mechanism, and therefore the

various details may be more or less changed without departing from the spirit or scope 55 of the present improvement.

The throat or cloth plate 1 has a raised portion 2 wherein the feed (not shown) operates. The presser foot 3 has an upturned toe 4 and is carried by the presser 60 bar 5 slidably mounted in a bushing 6 which is secured in a bearing 7 of the machine head 8. This head 8 is slotted at 9 to receive the end 10 of the presser bar 11, which is clamped to the presser 65 bar 5. This guide 11, extending through the slot 9, holds the presser foot 3 against lateral movement. To lift the presser foot 3, the usual lifting lever 12, operated by a floor treadle (not shown), is provided, and 70 this lever 12 coacts with an angle piece 13 carried by the guide 11 and lifts the presser foot against the action of the presser spring 14 engaging the top of the presser bar 5. A hand lifter 15 pivoted at 16 in 75 the slot 9 also acts against the bottom of the guide 11 to lift the presser foot. The needles 17 are carried by the needle bar 18, which has secured to its upper end a collar 19 connected with a pitman 20. The other 80 end of this pitman is connected to a crank pin 21 carried by a disk 22 secured to the end of the top rotary shaft 23 to give reciprocating motion to the needles. The crank pin 21 has an arm 24 extending toward the 85 center of the shaft 23, and this arm has a crank pin 25 connected with a bearing 26 of a tube 27. A piston 28 in this tube is pivotally connected at 29 to a ruffling bar 30, and this piston is provided with a stop 90 pin 31 working in a slot 32 of the tube 27. A coiled spring 33 surrounds the stem 34 of this piston 28, this stem extending through the cap 35 of the tube so that at its upper end the piston is guided by the cap 95 35 and also by the other end of the tube, the pin 31 limiting the downward movement thereof by means of the slot 32. The pivot 29 has extended ends operating in slots 36 of a yoke 37 also secured to the 100 presser bar 5. This yoke is slotted in front and at right angles to the pivot 29 to permit the ruffler bar 30 to be hinged thereto, so that when the presser foot is lifted either by hand or treadle the extended ends of the 105 pivot 29 resting in the bottom of the slot

36 effect a lifting of the ruffling bar 30 and cause the pin 31 to move upward in its slot 32 and so compress the spring 33 in the piston tube or casing, and thus arrests the 5 rise and fall movement of the ruffler bar 30 ordinarily given to it by the crank pin 25 and the piston casing or tube 27. The ruffling bar 30 is provided with a yoke piece 37 adjustably secured thereto, and this yoke 10 has a stud 38 for adjustably supporting the ruffling blade 39, which may be provided with the usual teeth. The ruffling bar 30 has a pin 41 to engage a notch 42 of a latch lever 43, which is pivoted at 44 to an arm 15 45. This lever 43 is provided with a handle 46 to manipulate it and unlatch it from the pin 41 so that the ruffler bar 30 and its ruffler blade may be swung into the dotted line position shown in Fig. 1, at which time 20 the spring 47, having one end attached to the arm 45 and its other end attached to the lever 43, swings the latch lever on its pivot 44 into the dotted line position. The head 8 is provided with bearings 49 for the 25 ruffler shaft 50, to the end of which shaft the hub of the arm 45 is secured. To the bearing 49 is attached a spring 52, (see Fig. 2), shaped at its end 53 to latch over and hold the ruffle bar 30 in its raised position. 30 The pin 41 is brought into engagement with the notch of the latch lever 43 when the ruffling blade 29 is in position for ruffling action. It is to be understood that the ruffling mechanism shown herein has a rise 35 and fall movement given to it by the crank pin 25 and its connecting mechanism, and in addition has an in-and-out movement imparted thereto by the arm 45 secured to the ruffler or rock shaft 50, which may be 40 actuated from the top shaft 23 in any well known manner.

From the foregoing it will be seen that when the machine is in operation and the ruffling blade is lifted to its dotted line position, there is very little motion imparted to it by the crank pin 25 and no motion whatsoever imparted to it by the arm 45, and that it can be readily thrown into and out of operative position while the machine 50 is in motion.

Secured to the presser bar bushing 6 is a block 55, (see Fig. 3), the hole 56 of which fits over the bushing. The front end of this block is slotted, as at 57, to fit around the 55 needle bar bushing 58 and is steadied against movement thereby. Secured to this block is a tube 59 to receive a rod 60. This rod is provided with a pin 61 operating in a guide slot 62 to prevent axial movement 60 of the rod 60. The rod 60 is slotted at its forward end to receive the flattened end 64 of a rod 65, these two rods being pivotally connected for hinge movement in one direction. The tube 59 is slotted at

67 and is provided with a clamping collar 68 and clamping means 69 so as to close the tube and grip the rod 65 when desired. A hook 70 is secured to the tube at one end for the reception of one end of a spring 71, the other end of which is 70 connected, as at 72, to an arm 73 of a cloth folder bracket secured to the outer end of the rod 65, as at 74. This bracket extends downward and is connected to a member 76 by means of bolts 77 which project through 75 elongated slots in said member to permit vertical adjustment thereof. This member 76 has a hub 78 bored to receive the stem 79 supporting a cloth folder 80 suspended free of the cloth plate 1, so that the goods 80 may pass thereunder to the stitching position while other goods pass over the plate 81 and through a scroll 82 to fold the edge thereof.

To shift the cloth folder into and out of position, it is merely necessary to loosen the clamping means 69, (see Fig. 3), grasp the hub 74 and draw the rods 60 and 65 forward against the tension of the spring 71 until the hinge 66 emerges from the end 90 of the tube. Instantly the pull of the spring 71 draws the parts into the dotted line position shown in Fig. 2, drawing the rod 65 up against the end of the tube and holding it securely. To again put the cloth 95 folder in operative position, the hinged rod 65 is drawn away from the end of the tube and so positioned that it will reenter the tube under the action of the spring 71, whereupon the clamp 69 is tightened to hold 100 it securely in operative position.

It will be understood that when the machine is used for stitching and ruffling one circular piece to another, as for instance petticoat work, the presser foot is raised 105 and one circular piece placed in position for stitching to the right of the needles. Then the second piece is placed under the presser foot to the left of the needles, the cloth folder being in the dotted line position shown in Fig. 2 and the ruffling blade in the dotted line position shown in Fig. 1. Thus, with these parts out of the way, the positioning and removal of the work is greatly facilitated. After the work has 115 been placed, the ruffling blade is put into working position and the work also inserted into the scroll. The presser foot is then lowered and the stitching commences. This operation is continued until the beginning 120 of the stitching has reached the cloth folder, at which time it is swung out of position, the ruffling blade also swung out of position and the stitching operation completed and the work removed.

The eyelets 83 constitute means for guiding the needle threads to the needles,—the vertical portion 84 being guided by a mem-

ber 85 and operating in a slot 86 of the head, and is secured at 87 to the collar 19 for reciprocating motion.

I claim as my invention:

5 1. In a sewing machine the combination of a rotary top driving shaft, a four-motion ruffling attachment connected to the top driving shaft for swinging movement relatively thereto, and means effective to permit the ruffling attachment to be swung away from its operative position.

10 2. In a sewing machine the combination of a rotary top driving shaft, a rock shaft, a ruffling attachment connected with said top driving shaft for swinging movement relatively thereto and having connection with the rock shaft only when in its operative position, and means effective to permit the ruffling attachment to be swung away from its operative position.

15 3. In a sewing machine, the combination of a top driving shaft and a rock shaft, a ruffling attachment connected with both of said shafts for swinging movement relatively thereto, a folder attachment also supported for swinging movement, and means effective to permit each of said attachments to be swung and lifted in the same direction a considerable distance away from its operative position independently of each other.

20 4. In a sewing machine, the combination of a rotary top driving shaft, a presser-foot bar, means for lifting the same, a ruffling attachment connected to and liftable with said presser-foot bar and also swingingly connected to said top driving shaft for movement into and out of its operative position.

25 5. In a sewing machine, the combination of a rotary top driving shaft, a presser-foot bar, means for lifting the same, a ruffling attachment connected with said presser-foot bar and liftable thereby, and also swingingly connected with said top driving shaft for movement into and out of its operative position, a suspended folder attachment swingingly supported for movement into and out of its operative position and means effective to permit each of said attachments to be swung away from its operative position independently of any movement of the presser-foot bar.

30 6. In a sewing machine, the combination of a presser foot bar, means for lifting the same, a ruffling attachment connected therewith and liftable thereby, a folder attachment, means effective to permit each of said attachments to be swung away from its operative position, means for imparting a rising and falling movement to the ruffling attachment, and means for imparting an in-and-out movement thereto, said first means including a piston.

35 7. In a sewing machine, the combination

of a presser foot bar, means for lifting the same, a ruffling attachment connected therewith and liftable thereby, a folder attachment, means effective to permit each of said attachments to be swung away from its operative position, means for imparting a rising and falling movement to the ruffling attachment, and means for imparting an in-and-out movement thereto, said first means including a piston and said last means including a latch the shifting of which will permit the ruffling attachment to be swung away from its operative position.

40 8. In a sewing machine, the combination of a rotary top driving shaft, a ruffling attachment, means pivotally suspending it from said top driving shaft and including means for imparting to said ruffling attachment a rising and falling movement, means for imparting a to and fro movement to said attachment, said means having a construction effective to permit the shifting of the ruffling attachment away from its operative position independently of the movement of any other operating part of the machine.

45 9. In a sewing machine, the combination of a ruffling attachment, means for supporting it in its operative position and including means for imparting thereto a rising and falling movement, and means for imparting an in-and-out movement thereto, said means having a construction effective to permit the shifting of the ruffling attachment away from its operative position and also having a construction whereby on the shifting of the ruffling attachment away from its operative position its rising and falling movement is diminished.

50 10. In a sewing machine, the combination of a rotary top driving shaft, a ruffling attachment, means for pivotally suspending it from said top driving shaft and including means for imparting thereto a rising and falling movement and means for imparting a to and fro movement thereto, said means having a construction effective to permit the shifting of the ruffling attachment away from its operative position independently of any other operating part of the machine, and also having a construction whereby on the shifting of the ruffling attachment away from its operative position its to and fro movement is prevented.

55 11. In a sewing machine, the combination of a ruffling attachment, means for supporting it in its operative position and including means for imparting thereto a rising and falling movement, and means for imparting an in-and-out movement thereto, said means having a construction effective to permit the shifting of the ruffling attachment away from its operative position and also having a construction whereby on the shifting of

- the ruffling attachment away from its operative position its rising and falling movement is diminished and its in-and-out movement prevented.
12. In a sewing machine, the combination of a ruffling attachment, means for supporting it in its operative position and including means for imparting thereto a rising and falling movement, and means for imparting an in-and-out movement thereto, said means having a construction effective to permit the shifting of the ruffling attachment away from its operative position and also having a construction whereby on the shifting of the ruffling attachment away from its operative position its rising and falling movement is diminished and its in-and-out movement prevented, the means for imparting rising and falling movement including a piston.
13. In a sewing machine, the combination of a ruffling attachment, means for supporting it in its operative position and including means for imparting thereto a rising and falling movement, and means for imparting an in-and-out movement thereto, said operating means having a construction effective to permit the shifting of the ruffling attachment away from its operative position and also having a construction whereby on the shifting of the ruffling attachment away from its operative position its rising and falling movement is diminished and its in-and-out movement prevented, the means for imparting in-and-out movement including a latch the shifting of which will permit the ruffling attachment to be swung out of its operative position.
14. In a sewing machine, the combination of a ruffling attachment, means for supporting it in its operative position and including means for imparting thereto a rising and falling movement, and means for imparting an in-and-out movement thereto, said operating means having a construction effective to permit the shifting of the ruffling attachment away from its operative position and also having a construction whereby on the shifting of the ruffling attachment away from its operative position its rising and falling movement is diminished and its in-and-out movement prevented, the means for imparting rising and falling movement including a piston and the means for imparting in-and-out movement including a latch the shifting of which will permit the ruffling attachment to be swung out of its operative position.
15. In a sewing machine having a driving shaft and a rock shaft, the combination of a ruffling attachment having a piston connection with said driving shaft whereby a rising and falling movement is imparted to the ruffling attachment and having connection with said rock shaft whereby an in-and-out movement is imparted to said ruffling attachment, and means for lifting said ruffling attachment away from its operative position.
16. In a sewing machine having a driving shaft and a rock shaft, the combination of a ruffling attachment having a piston connection with said driving shaft whereby a rising and falling movement is imparted to the ruffling attachment and having a latch connection with said rock shaft whereby an in-and-out movement is imparted to said ruffling attachment, and means for shifting the ruffling attachment out of its operative position.
17. In a sewing machine having a driving shaft and a rock shaft, the combination of a ruffling attachment having a piston connection with said driving shaft whereby a rising and falling movement is imparted to the ruffling attachment and having connection with said rock shaft whereby an in-and-out movement is imparted to said ruffling attachment, and means for lifting the ruffling attachment.
18. In a sewing machine having a driving shaft and a rock shaft, the combination of a ruffling attachment having a piston connection with said driving shaft whereby a rising and falling movement is imparted to the ruffling attachment and having a latch connection with said rock shaft whereby an in-and-out movement is imparted to said ruffling attachment, whereby on the shifting of said latch the ruffling attachment may be shifted out of its operative position, and means for lifting the ruffling attachment.
19. In a sewing machine having a driving shaft and a rock shaft, the combination of a ruffling attachment having a piston connection with said driving shaft whereby a rising and falling movement is imparted to the ruffling attachment and having connection with said rock shaft whereby an in-and-out movement is imparted to said ruffling attachment, a presser foot bar connected with said ruffling attachment, and means for lifting said presser foot bar and thereby the ruffling attachment.
20. In a sewing machine having a driving shaft and a rock shaft, the combination of a ruffling attachment having a piston connection with said driving shaft whereby a rising and falling movement is imparted to the ruffling attachment and having a latch connection with said rock shaft whereby an in-and-out movement is imparted to said ruffling attachment, whereby on the shifting of said latch the ruffling attachment may be shifted out of its operative position, a presser foot bar connected with said ruffling attachment, and means for lifting said presser foot bar and thereby the ruffling attachment.
21. In a sewing machine having a rotary

top driving shaft and a rock shaft, a presser foot bar and means for lifting the same, the combination of a ruffling attachment operatively connected with said presser-foot bar 5 and liftable therewith, means pivotally connecting said attachment with the driving shaft for imparting a rising and falling movement thereto, and means connecting said attachment with the rock shaft, whereto 10 by a to and fro movement is imparted thereto, the said two connecting means constructed to permit the swinging of the ruffling attachment away from its position independently of any movement of the presser-foot 15 bar.

22. In a sewing machine having a driving shaft and a rock shaft, a presser foot bar and means for lifting the same, the combination of a ruffling attachment operatively 20 connected with said presser foot bar and liftable therewith, means connecting it with the driving shaft whereby a rising and falling movement is imparted to said attachment, and means connecting it with the rock 25 shaft whereby an in-and-out movement is imparted to said attachment, the said two connecting means constructed to permit the swinging of the ruffling attachment away from its operative position independently of 30 any movement of the presser foot bar and when in such inoperative position to prevent the ordinary movements thereof.

23. In a sewing machine having a driving shaft and a rock shaft, a presser foot bar 35 and means for lifting the same, the combination of a ruffling attachment operatively connected with said presser foot bar and liftable therewith, piston connecting means operatively connecting said ruffling attachment with the driving shaft whereby a rising and falling movement is imparted to 40 said ruffling attachment, and latch connecting means operatively connecting said ruffling attachment with the rock shaft whereby in-and-out movement of the ruffling attachment is effected and whereby on the shifting of the latch the ruffling attachment 45 may be swung into its inoperative position.

24. In a sewing machine having a driving shaft and a rock shaft, a presser foot bar and means for lifting the same, the combination of a ruffling attachment operatively connected with said presser foot bar and liftable therewith, piston connecting means 50 operatively connecting said ruffling attachment with the driving shaft whereby a rising and falling movement is imparted to said ruffling attachment, and latch connecting means operatively connecting said ruffling attachment with the rock shaft whereby in-and-out movement of the ruffling attachment is effected and whereby on the shifting of the latch the ruffling attachment 55 may be swung into its inoperative position,

the said connecting means constructed so 65 that on the swinging of the ruffling attachment away from its operative position the ordinary movements thereof are prevented.

25. In a sewing machine having a driving shaft and a rock shaft, a presser foot bar and means for lifting the same, the combination of a ruffling attachment comprising a ruffler bar operatively connected with the presser foot bar and liftable therewith, a 70 ruffler connected with said ruffler bar, a spring pressed piston connection between said ruffler bar and driving shaft, a depending arm connected with the rock shaft, and a latch connection between said depending arm and said ruffler bar. 75

26. In a sewing machine having a driving shaft and a rock shaft, the combination of a ruffling attachment comprising a ruffler bar, piston connecting means between said ruffler bar and the driving shaft, a ruffler carried by said bar, a depending arm carried by the rock shaft, and a latch connection between said depending arm and ruffler bar. 85

27. In a sewing machine having a driving shaft and a rock shaft, the combination of a ruffling attachment comprising a ruffler bar, piston connecting means between said ruffler bar and the driving shaft, a ruffler carried by said bar, a depending arm carried by the rock shaft, a latch connection between said depending arm and ruffler bar, and means for lifting said ruffler bar. 90

28. In a sewing machine having a driving shaft and a rock shaft, the combination of a ruffling attachment comprising a ruffler bar, piston connecting means between said ruffler bar and the driving shaft, a ruffler carried by said bar, a depending arm carried by the rock shaft, a latch connection between said depending arm and ruffler bar, 100 means for lifting said ruffler bar, and a folder attachment. 105

29. In a sewing machine having a driving shaft and a rock shaft, the combination of a ruffling attachment comprising a ruffler bar, piston connecting means between said ruffler bar and the driving shaft, a ruffler carried by said bar, a depending arm carried by the rock shaft, a latch connection between said depending arm and ruffler bar, 110 means for lifting said ruffler bar, and a folder attachment shiftable into and out of its operative position independently of said ruffler. 115

30. In a sewing machine having a driving shaft and a rock shaft, the combination of a ruffling attachment comprising a ruffler bar, piston connecting means between said ruffler bar and the driving shaft, a ruffler carried by said bar, a depending arm carried by the rock shaft, a latch connection between said depending arm and ruffler bar, 120 means for lifting said ruffler bar, and a 125

- folder attachment supported to permit the swinging thereof away from its operative position.
31. In a sewing machine having a driving shaft and a rock shaft, the combination of a ruffler attachment comprising a ruffler bar, piston connecting means between said ruffler bar and the driving shaft, a ruffler carried by said bar, a depending arm carried by the rock shaft, a latch connection between said depending arm and ruffler bar, means for lifting said ruffler bar, and a folder attachment supported to permit the swinging thereof away from its operative position and comprising a casing, a pair of hinge-connected bars therein partly withdrawable from said casing to permit the swinging of one relatively to the other and a folder carried by one of said bars.
32. In a sewing machine, the combination of a sewing machine attachment and fixed means for supporting it on the machine for sliding movement in a horizontal plane and then for lateral swinging movement to permit the attachment to be moved away from its operative position.
33. In a sewing machine, the combination with ruffling mechanism and means for operating the same, of a folder attachment including a folder shiftable away from its operative position and comprising a casing, a pair of hinged bars therein and partly withdrawable from said casing to permit the swinging of one relatively to the other, and a spring for maintaining said bars within said casing.
34. In a sewing machine having a driving shaft and a rock shaft, a presser foot bar and means for lifting the same, the combination of a ruffling attachment comprising a ruffler bar operatively connected with the presser foot bar and liftable therewith, means connecting said ruffler bar with the driving shaft for imparting a rising and falling movement to the ruffler bar, means connecting the ruffler bar with the rock shaft for imparting an in-and-out movement to the ruffler bar, said last connecting means effective to permit the swinging of the ruffler bar away from its operative position independently of any movement of the presser foot bar, and a ruffler carried thereby.
35. In a sewing machine having a driving shaft and a rock shaft, a presser foot bar and means for lifting the same, the combination of a ruffling attachment comprising a ruffler bar operatively connected with the presser foot bar and liftable therewith, means connecting said ruffler bar with the driving shaft for imparting a rising and falling movement to the ruffler bar, means connecting the ruffler bar with the rock shaft for imparting an in-and-out movement to the ruffler bar, said last connecting means effective to permit the swinging of
- the ruffler bar away from its operative position, a ruffler carried thereby, and a folder shiftable into and out of position independently of said ruffler.
36. In a sewing machine having a driving shaft and a rock shaft, a presser foot bar and means for lifting the same, the combination of a ruffling attachment comprising a ruffler bar operatively connected with the presser foot bar and liftable therewith, means connecting said ruffler bar with the driving shaft for imparting a rising and falling movement to the ruffler bar, means connecting the ruffler bar with the rock shaft for imparting an in-and-out movement to the ruffler bar, said last connecting means effective to permit the swinging of the ruffler bar away from its operative position, a ruffler carried thereby, and a folder comprising a casing, a pair of hinged bars sliding within said casing, and a folder connected with one of said bars whereby on the partial withdrawal of said bars the folder may be swung away from its operative position.
37. In a sewing machine having a driving shaft and a rock shaft, a presser foot bar and means for lifting the same, the combination of an attachment supporting bar operatively connected with said presser foot bar adjacent to the upper end thereof, means operatively connecting it with the driving shaft for imparting movement to said bar, means operatively connecting it with the rock shaft whereby movement is imparted to said bar, said last means permitting the swinging of said bar away from its operative position, and an attachment connected to said bar.
38. In a sewing machine having a driving shaft and a rock shaft, a presser foot bar and means for lifting the same, the combination of an attachment supporting bar operatively connected with said presser foot bar, means operatively connecting it with the driving shaft for imparting movement to said bar, means operatively connecting it with the rock shaft whereby movement is imparted to said bar, said last means including a latch and permitting the swinging of said bar away from its operative position, and an attachment connected to said bar.
39. In a sewing machine having a driving shaft and a rock shaft, a presser foot bar and means for lifting the same, the combination of an attachment supporting bar operatively connected with said presser foot bar, means operatively connecting it with the driving shaft for imparting movement to said bar, means operatively connecting it with the rock shaft whereby movement is imparted to said bar, said last means permitting the swinging of said bar away from its operative position, a casing, a pair of hinged bars sliding within said casing, and

an attachment carried by one of said hinged bars whereby on the partial withdrawal of said bars said attachment may be swung into its inoperative position.

- 5 40. In a sewing machine having a driving shaft and a rock shaft, a presser foot bar and means for lifting the same, the combination of an attachment supporting bar operatively connected with said presser foot bar, 70
10 means operatively connecting it with the driving shaft for imparting movement to said bar, means operatively connecting it with the rock shaft whereby movement is imparted to said bar, said last means including 15 a latch and permitting the swinging of said bar away from its operative position, a casing, a pair of hinged bars sliding within said casing, and an attachment carried by one of said hinged bars whereby on the partial withdrawal of said bars said attachment 20 may be swung into its inoperative position.

41. In a sewing machine having a driving shaft and a rock shaft, a presser foot bar and means for lifting the same, the combination of an attachment supporting bar operatively connected with said presser foot bar, 75
25 means operatively connecting it with the driving shaft for imparting movement to said bar, means operatively connecting it with the rock shaft whereby movement is imparted to said bar, said last means including 30 a latch and permitting the swinging of said bar away from its operative position, a casing, a pair of hinged bars sliding within said casing, and an attachment carried by one of said hinged bars whereby on the partial withdrawal of said bars said attachment 35 may be swung into its inoperative position, one of said attachments comprising a ruff- 40 fling blade and the other a scroll folder.

42. In a sewing machine, the combination of a top driving shaft, ruffling mechanism suspended from and crank connected with said top driving shaft, whereby a rising and falling movement is imparted thereto, means for imparting a to and fro movement to the ruffler, and means for disconnecting it from one of its operating means, whereby it may be thrown into and out of its operative position at any time during the stitching operation.

43. In a sewing machine, the combination of a top driving shaft, ruffling mechanism suspended from and crank connected with 55 said top shaft, thereby to impart a rising and falling movement to said ruffling mechanism, means for imparting a to and fro movement to the ruffler, and means for disconnecting it from the means for imparting a to and fro movement thereto, whereby it may be thrown into and out of its operative position at any time during the stitching operation.

44. In a sewing machine, the combination 60 of a presser-foot, means for lifting the same,

a ruffling attachment having a pin and slot connection with said presser-foot and liftable therewith, means for operating said ruffling attachment, and means for disconnecting it from a part of its operating means, whereby it may be thrown into and out of its operative position either before or after the lifting of the presser-foot.

45. In a sewing machine, the combination of a top driving shaft and a rock shaft, a 75 presser-foot, means for lifting the same, a hanging ruffling attachment connected to and liftable with said presser-foot, means connected with said top driving shaft and rock shaft for operating said ruffling attachment, means for disconnecting it from a part of its operating means, whereby it may be thrown into and out of its operative position either before or after the lifting of the presser-foot, and a hanging folder attachment shiftable into and out of its operative position independently of said ruffling attachment.

46. In a sewing machine having a driving shaft and a rock shaft, the combination of 90 a ruffling attachment having connection with said driving shaft whereby a rising and falling movement is imparted to the ruffling attachment and having a detachable connection with said rock shaft whereby an in and out movement is imparted to said ruffling attachment, and means for effecting a disconnection of the ruffling attachment from the rock shaft to permit the shifting of the ruffling attachment out of 95 the way.

47. In a sewing machine, the combination of a rotary top driving shaft, a ruffling attachment hanging from and connected with said shaft for operation thereby, operating 105 means for imparting a to and fro movement to the ruffler attachment, means effective to permit a disconnection of the ruffling attachment from a part of its operating means, whereby said ruffling attachment may be 110 shifted out of the way, a hanging folder attachment, and means effective to permit the shifting of the folder attachment out of the way independently of the ruffling attachment.

48. In a sewing machine having a rotary top driving shaft and a rock shaft, the combination of a ruffling attachment having connection with and hanging from said driving shaft, and also having connection with the rock shaft, and means for disconnecting it from one of said shafts, thereby to permit the shifting thereof into its inoperative position.

49. In a sewing machine having a rotary 120 top driving shaft and a rock shaft, the combination of a ruffling attachment having connection with and hanging from said top driving shaft and also having connection with the rock shaft, and means for discon- 125

130

necting it from the rock shaft, thereby to permit the shifting thereof into its inoperative position.

50. In a sewing machine having a driving shaft and a rock shaft, the combination of an attachment pivotally connected with said driving shaft whereby a rising and falling movement is imparted to said attachment and having detachable connection with 10 said rock shaft whereby an in and out movement is imparted to said attachment, and means effective to permit the disconnection of said attachment from said rock shaft whereby the attachment may be swung away 15 from its operative position.

51. In a sewing machine having a driving shaft and a rock shaft, the combination of an attachment pivotally connected with said driving shaft whereby a rising and falling movement is imparted to said attachment and having detachable connection with 20 said rock shaft whereby an in and out movement is imparted to said attachment, means effective to permit the disconnection of said attachment from said rock shaft whereby the attachment may be swung away from its 25 operative position, a presser foot bar, means

for lifting it, and means connected with said bar and with said attachment whereby the attachment may be lifted on the lifting 30 of the presser foot bar.

52. In a sewing machine having a driving shaft and a rock shaft, the combination of an attachment pivotally connected with said driving shaft whereby a rising and falling movement is imparted to said attachment and having detachable connection with 35 said rock shaft whereby an in and out movement is imparted to said attachment, means effective to permit the disconnection of said attachment from said rock shaft whereby the attachment may be swung away from 40 its operative position, a presser foot bar, means for lifting it, and means connected with said bar and with said attachment at 45 the point of its pivotal connection with the driving shaft whereby the attachment may be lifted on the lifting of the presser foot bar.

Signed at Boston, in the county of Suffolk 50
and State of Massachusetts, this 14th day
of January, 1916.

WILLIS C. ROBBINS.
